DOOR CONSTRUCTION

Joseph Tesek, Cleveland, Ohio

Application August 18, 1933, Serial No. 685,728

1 Claim. (Cl. 20—35)

This invention relates to a door construction and in particular to a fabricated wood door having veneered surfaces.

It is well known to those skilled in the art that regardless of the treatment of the constituent elements of now used fabricated wood doors there is a certain amount of distortion or warping when in use, and that this distortion or warping is very difficult to eliminate or appreciably minimize.

It is a general object of my invention to provide an improved fabricated, veneered surface, door construction which will either entirely eliminate or greatly minimize the tendency of a door to warp or distort throughout its life, regardless of varying weather and temperature conditions.

It is another object of my invention to provide a door construction of this character comprising mainly scrap or relatively inexpensive wood elements interiorly thereof and finished of relatively more expensive woods arranged exteriorly thereof, so as to produce a door giving the appearance of a very expensive construction, but in reality being relatively inexpensive to manufacture.

Another object is to provide a door of the veneered surface type having a core member of scrap or similarly inexpensive material assembled in cooperative arrangement with frame elements of relatively more expensive material, and having veneered surfaces comprised of alternate strips of different kinds of woods, whereby the combination and arrangement of woods chosen for the core, frame and veneer elements is such as to entirely eliminate the distortion or warping tendency of the assembled structure.

Another object is to provide a door construction having core and frame members and a plurality of strips overlying the frame and core members, one of the strips spanning across or overlying the frame and core elements in such a fashion as to hold these in rigid assembly or alignment and thereby eliminate or greatly minimize any tendency toward relative movement between these elements.

The invention therefore resides in the particular combination and arrangement of elements in a fabricated, veneered-surface, wood door construction as will hereinafter appear in the specification and drawings, in which

Fig. 1 is an elevation of a door embodying my invention.

Fig. 2 is a side elevation of the door shown in Fig. 1.

Fig. 3 is a cut-away elevation of the door pic-

tured in Fig. 1, showing the elements in its construction.

Fig. 4 is an end view of that in Fig. 3.

Fig. 5 is a detail of a core unit.

Fig. 6 is an end view of that in Fig. 5.

Fig. 7 is another embodiment of my invention showing another arrangement of elements.

Fig. 8 is a detail of a construction for curved end doors.

Referring now particularly to Figs. 1, 2, 3 and 10, I have illustrated a door having a core construction 10, preferably comprised of glued together scrap wood of pine, chestnut, or like relatively inexpensive woods, tongued and grooved along opposing parallel edges thereof, as at 12, 15 with binder strips 14. The grain of the component elements making up the core 10 preferably extends laterally of the door, that is left to right or right to left as viewed in Fig. 3, while the grain of the binder strip 14, which may also be fabricated from scrap or relatively inexpensive woods similar to that used in the core 10, preferably extends at right angles to the grain in the core 10. Circumscribing the assembled core and binder strips and flush therewith are shown rail 25 members 16 and stile members 18. These members are preferably of finish woods, such for example as walnut, or other highly polishable wood. The stile and rail members are interfitted at their junctions as at 20. This interfitting is preferably 30 of a dovetail construction as is more clearly shown in Fig. 4.

The core 10, binder strips 14, the rail elements 16, and stile elements 18 are assembled and glued together by any of the well known processes 35 commonly used in the art. Overlying this assembly on both sides is adhered, as by gluing, a plurality of veneer strips 22, 23, 24, 25, 26, 27 and 28, arranged in edge to edge fashion and the outermost of these extending for the full vertical 40 dimension of the assembly, that is, from the top rail to the bottom rail. While I have shown a definite number of veneer strips, it is to be understood that any other number may be used with the limitations hereinafter to be noted. 45 These strips 22 to 28 inclusive are preferably different kinds of wood, as will more fully herein-after be described, and have their grain extending lengthwise of the strip. The entire surface of the door, including the edges, being of finished 50 wood, may be polished to present a pleasing appearance and give the effect of a door of expensive manufacture.

By using a binder strip of relatively cheap woods less of the finished or relatively more ex- 55

pensive wood is required for the rail and stile elements, and only finished or hard woods are presented to the view while at the same time maintaining both rigidity and long wearing qualities of the door.

In the assembly of the veneer strips 22 to 28, inclusive, with the core, binder, and frame elements described, it is essential that the outermost strips, for example strips 22 and 28, span over the stile members 18, binder elements 14, and a portion of the core 10, as illustrated in Fig. 3. The function of the binder strip 14 with its tongue and groove connection with the core 10 is to prevent any tendency of the core 10 to distort in a plane normal to the paper, as viewed in Fig. 3, while the function of the rail members 16 and the stile members 18, with their interfitting joints 20, is to prevent any distortion of the frame elements in a direction in the plane of the paper. By arranging the outside veneered strips 22 and 28 so that they span, respectively, over the underlying stile and binder members and the adjacent core portions for the full length thereof, the stile, binder and core are held tightly in assembled relation, thereby further preventing any tendency of the structure to distort or warp. By further making the veneer strips 22 to 28 of different kinds of woods, which are affected diversely by weather and temperature conditions, the tendency to warp or distort is further inhibited.

I have found by experimentation that certain classes of woods may be used for the veneer strips 22 to 28, inclusive, which in addition to providing a door of rigid construction substantially eliminating or greatly minimizing any tendency to warp or distort, also provides for a door having a highly polishable surface, possessing characteristics of beauty and adaptable to combinations thereof in harmony with the new modernistic motif. While it is possible to work out a number of combinations of different woods for these strips, the following are known to be particularly effective, both as regards construction and appearance, and I desire that they shall form a part of my invention.

One combination of this character comprises the arranging of the strips such that the strips 22, 25 and 28 are of walnut, while the strips 23 and 27 are of birch, and the strips 24 and 26 of gum.

Another combination comprises making the strips 22, 25 and 28 of gum, the strips 23 and 27 of birch, and the strips 24 and 26 of walnut.

Still another combination is an arrangement whereby the strips 22, 25 and 28 are of birch, the strips 23 and 27 are of gum, and the strips 24 and 26 are of walnut.

Yet another combination comprises alternate strips of mahogany or cherry and birch.

While I have shown the core 10 in Fig. 3 as being of a single unit comprised of scrap woods glued together, this may also be comprised of individual units assembled together, each unit in itself being comprised of scrap woods glued together, such as is depicted in Figs. 5 and 6. As there shown, a unit 30 may be made up of scrap or end woods glued together and along parallel edges thereof a tongue 32 may be formed to interfit with a corresponding groove in the binder member 14 as heretofore described.

It will be apparent that the rail, stile, binder and core members described may be cut to fixed dimensions corresponding to standard door sizes and carried in stock ready for assembly with desired veneer strips selected or specified on order.

It will also be apparent from the construction

illustrated that the assembly is adapted to high speed and cheap production manufacture at a relatively low cost, thereby making possible the supply at low cost of an expensive appearing door for ordinary or relatively low priced homes. 5

I am aware that there are circumstances or tastes which are not favorable to the use of veneer strips as heretofore described and I therefore contemplate within my invention a door construction of less mechanical perfection but 10 having a smooth veneered surface. Such a door construction is illustrated in Fig. 7. As there shown, a core 34, built up similar to the heretofore described core 10 but having its grain extending vertically, as viewed in Fig. 7, is circumscribed by rail members 36 and stile members 38 joined at 40 as heretofore described and glued in flush assembly with the core 34. Overlying the assembled core, rail and stile members is shown an intermediate veneer 42 extending 20 transversely of the door in unbroken section for the full distance thereof and being in adhesive contact with the opposite stile members 38, and having its grain extending at right angles to the grain of the core 34. Overlying the intermediate 25 ply or veneer 42 and having its grain extending at right angles to the grain of the ply 42 is a second or finish veneer 44. It is essential for the purposes of this invention that the plies or veneers 42 and 44 and the core 34 have their grain 30 extending in the relative directions indicated. The assembly as shown in Fig. 7 is preferably adhered together by gluing or a similar process.

While all of the embodiments thus far have been shown as having straight edges, it is to be understood that my invention is not limited to such but is adapted to have curved edges by such a construction as is illustrated in Fig. 8. As there shown a door which is to have a curved edge cut along the broken lines 46 may have its rail 40 element 48 comprised of a plurality of elements 50, 52 and 54 interfitting along coacting edges, as shown at 56 and 58, and joined with stile members 60 by interfitting connections as shown at 62. The elements 50, 52 and 54 are preferably 45 arranged with respect to each other and respect to the stiles 60, so that a minimum of material is required to effect connection therebetween and to permit of the cutting of the arc along the line 46 without undue waste of the material so cut 50 off. A core 64 may be assembled with these elements as indicated and in the manner heretofore described.

While I have illustrated certain specific embodiments of my invention, it is to be understood that certain modifications and other embodiments may be made without departing from the spirit and scope of the invention as defined in the appended claims. Further, it will be obvious that 60 while I have shown embodiments in the door art my invention is also applicable to the manufacture of table tops, desk tops, dresser tops, and other like articles of furniture. Where therefore the particular nomenclature used in the claims 65 refers specifically to the door art it is to be understood that their equivalents or counterparts in other arts are also intended. Also, for the purpose of convenience in the claims I have referred to the woods comprising the binder and 70 core elements as being "unfinished" woods, that is, scrap or relatively coarse woods, and the woods comprising the rail, stile and finish veneers as being "finished" woods, that is, hard woods adapted to have a polished surface. 75

I claim:

The combination of a core, binder members tongued and grooved with and along opposing edges of said core, frame elements circumscribing said binder members and core, a plurality of veneer strips of different kinds of wood overlying said frame, binder and core members, the upper

portion of said core being narrow to receive a rail element comprising a plurality of members interfitting along co-acting edges, said elements being so positioned with respect to each other that a rounded portion may be cut by sawing through said latter members of the frame. ⁵

JOSEPH TESEK.
